M. Glass

INVENTOR

BY *Victor J. Evans*

ATTORNEY

UNITED STATES PATENT OFFICE.

MATTHEW GLASS, OF PHILADELPHIA, PENNSYLVANIA.

HOLDER.

1,423,415.

Specification of Letters Patent. Patented July 18, 1922.

Application filed October 8, 1921. Serial No. 506,425.

To all whom it may concern:

Be it known that I, MATTHEW GLASS, a citizen of the United States, residing at Philadelphia, in the county of Philadelphia and State of Pennsylvania, have invented new and useful Improvements in Holders, of which the following is a specification.

This invention relates to improvements in holders.

10 An object of the invention is to provide a strong and durable device embodying novel features of construction whereby a movable jaw and a stationary jaw are adapted to receive a cloth or wad of paper serving as a 15 mop for cleaning purposes and retain the same in adjusted position.

Another object is to provide a simple and efficient device which is formed from two strands of galvanized wire and can be manufactured at a very low cost.

With the above and other objects in view, the invention consists in certain novel features of construction, combination and arrangement of parts, as will be more fully described and particularly pointed out in the appended claims.

In the accompanying drawings,

Figure 1 is a perspective view of the invention.

30 Figure 2 is a perspective view of the stationary member.

Referring now to the drawings, in which like characters of reference designate corresponding parts throughout the several views, the numeral 10 designates a movable member which is formed from one strand of wire and comprises a substantially U-shaped jaw 11 which extends at right angles from a pair of parallel arms 12 and 13. A relatively short shank 14 disposed in a plane parallel to the arms 12 and 13 and terminating in a handle 15 extends at right angles from an elbow 16 extending at right angles from one end of the arm 12. An elbow 17 in alignment with the elbow 16 extends at right angles from the arm 13 and is bent around the adjacent end of the shank 14.

A stationary member 18 is formed from the second strand of wire and comprises a 50 substantially U-shaped jaw 19 which is parallel to the jaw 11.

The parallel sides of the jaw 19 are bent upon themselves to provide spaced guide

eyes 20 and 21 which receive the parallel arms 12 and 13 respectively, of the movable member. A relatively long shank 22 is disposed in a plane at right angles to the jaw 19 and extends at right angles from an elbow 23 which is disposed in a plane parallel to the elbow 16 and extends inwardly from the eye 20. An elbow 24 extends inwardly from the eye 21 and is bent around the adjacent end of the shank 22. A handle 25 is formed at the opposite end of the shank and is in a plane parallel to the handle 15 while intermediate its length the shank 22 is bent upon itself to provide a guide loop 26 which receives the shank 14 of the movable member.

In use, a cloth or wad of paper is placed between the jaws 11 and 19 and the handle 15 is moved toward the handle 25 thereby securing the cloth or wad of paper in place for instant use. After the cleaning is finished, the handle 15 is released thus permitting the cloth or wad of paper to be removed.

While it is believed that from the foregoing description the nature and advantages of the invention will be readily apparent, I desire to have it understood that I do not limit myself to what is herein shown and described, and that such changes may be resorted to when desired as fall within the scope of what is claimed.

What I claim is:

1. A device of the class described comprising a stationary jaw provided with spaced guide eyes and a shank disposed in a plane at right angles to said jaw and provided with a guide loop, a handle extending from said shank, a movable jaw parallel to said stationary jaw, parallel arms extending at right angles from said movable jaw and extending through the guide eyes of said stationary jaw, a shank connected to said parallel arms disposed in a plane parallel with said arms and extending through the guide loop of the first mentioned shank, and a handle extending from the last mentioned shank and disposed in a plane parallel to the handle afore- 95 said.

2. A device of the class described comprising a substantially U-shaped stationary jaw provided with spaced guide eyes, elbows extending inwardly from said eyes, a relatively long shank extending from one of

said elbows and provided with a guide loop, a handle extending from said shank, a substantially U-shaped movable jaw parallel to said stationary jaw, arms extending at right angles from said movable jaw and extending through said guide eyes, elbows extending inwardly from said arms, a relatively short

shank extending from one of the last mentioned elbows and extending through said guide loop and a handle extending from the 10 last mentioned shank.

In testimony whereof I affix my signature.

MATTHEW GLASS.
